AIR CONDITIONING SYSTEM

Lawrence A. Philipp, Detroit, Mich., assignor, by
mesne assignments, to Nash-Kelvinator Cor-
poration, Detroit, Mich., a corporation of
Maryland

Application November 14, 1933, Serial No. 697,939
Renewed July 16, 1936

12 Claims. (Cl. 62—6)

The present invention relates to refrigeration and more particularly to air conditioning system in which a refrigerating apparatus is utilized for conditioning the air.

- 5 One of the objects of the present invention is to provide a refrigerating apparatus employing a plurality of evaporators of the type in which the flow of refrigerant to the same is responsive to the condition of the refrigerant in the respective 10 evaporator, and circulating refrigerating medium through the evaporators in such a manner that the temperature differential between the same may be attained by providing for different suction pressures at the outlets of the evaporators, 15 and to provide for interconnecting the outlets of the evaporators so as to at times maintain a substantially uniform temperature of the evaporators; to control the interconnection of the outlets of the evaporators in response to the relative 20 humidity of the air which is to be conditioned by the evaporators; to connect a plurality of evaporators with a plurality of sources of low pressure and to at times connect each evaporator individually with a source of low pressure and at 25 times interconnect the evaporators with one another and with a plurality of these sources of reduced pressure.

Other and further objects and advantages will be apparent from the following disclosure, reference being had to the accompanying drawing wherein a preferred form of embodiment of the present invention is clearly shown.

The figure in the drawing represents more or less diagrammatically my improved refrigerating apparatus and air conditioning system.

Referring to the drawing, I have illustrated the air conditioning system as being applied to cooling a room such as an office or a room in a dwelling. The room is indicated as 20 and a wall 21 40 and a floor 22 of the room are shown. A cabinet 24 is disposed within the room 20 and is provided with an air inlet opening 25 and an air outlet opening 26. A partition 29 depends from the top wall of the cabinet and extends from the 45 front to the rear of the cabinet for directing air. A fan 27 driven by a motor 28 causes air to circulate through the cabinet 24. Any form of heat absorbing element may be employed and I have herein illustrated an element comprising evap- 50 orators or evaporator sections 30 and 31, each including a coil provided with fins 32 for increasing the heat absorbing surface 30. The evaporator 31 has approximately as much heat absorbing surface as evaporator 30. Air from the room 20 enters the cabinet 24 through the inlet 25 and approximately one-half of the air is forced over the evaporator 30 and the other half thereof is forced over the evaporator 31 and then out of the cabinet through the opening 26. The means for circulating refrigerating medium through the 5 heat absorbing elements provides a plurality of sources of reduced pressure and is herein shown as comprising a multiple cylinder compressor 35 having a cylinder 36 and a cylinder 37. This compressor is of the reciprocating type and the cylinder 36 is provided with an inlet 38 and the cylinder 37 is provided with an inlet 39. The inlet 38 also communicates with the crank case of the compressor for withdrawing gaseous refrigerant therefrom. The outlets for the compressed fluid are connected with one another at 40. The compressor is driven by a motor 42 and a reduction gearing may be employed between the motor 42 and compressor 35 if so desired.

20 Gaseous refrigerant which enters the inlets 38 and 39 is compressed by the compressor, forced into a condenser 43 where it is cooled and liquefied and then into a receiver 44 whence it is conducted by a pipe 45 and branch pipes 46 and 47 to expansion valves 48 and 49. These valves 25 48 and 49 control the flow of refrigerant to their respective evaporators 30 and 31 in accordance with the condition of the refrigerant in the respective evaporators. Each valve is responsive to the pressure within an evaporator. A reduction in pressure within the evaporator tends to open the valve to admit liquid refrigerant to the evaporator but this opening of the valve is modified by a thermostat 50. The thermostats 30 35 are bonded to the outlets of the evaporators 30 and 31 and are connected to the back side of the expansion valves 48 and 49 by tubes 51. The thermostats 50 and 51 contain a volatile fluid and therefore vary the pressure on the back sides of the valves 48 and 49 and are adjusted to prevent or substantially prevent the flow of refrigerant to the evaporators when vaporization of refrigerant is taking place at the outlets of the evaporators. Such valves are known in the art as thermostatic expansion valves. The outlet of 40 evaporator 31 is connected to inlet 38 of cylinder 36 by a pipe 55. A pipe 57 connects the outlet of evaporator 30 to the chamber 58 of an oil trap 60 and gaseous refrigerant passing from evaporator 30 flows through pipe 51, chamber 58 and 45 through a pipe 61 to the inlet 39 of cylinder 37. An oil outlet of chamber 58 is connected by a pipe 63 with the crank case of compressor 35 and is arranged to deliver entrained oil to the crank case. The outlet of the oil trap is con- 50 55

trolled by a float actuated valve 64 which opens the outlet after a predetermined quantity of oil is collected within the chamber 58.

5 and 30 are arranged to be interconnected by pipes 65, valve 66 and pipe 67. The valve 66 comprises a solenoid core 68 which is arranged to open and close the valve 66. This core 68 when raised by an electro-magnet 69 opens the outlet 10 of the valve 66 to establish connection between the pipe 55 and pipe 57.

Gaseous refrigerant which is withdrawn from evaporators 30 and 31 is compressed by the compressor 35 condensed in the condensers 43 and 15 is delivered to thermostatic expansion valves 48 and 49. A part of the refrigerant vaporizes in evaporator 30 and the vaporized refrigerant passes through pipe 57 whence it is delivered to the inlet 39 of cylinder 37 and, part of the refrigerant vaporizes in evaporator 31. The gaseous refrigerant then passes by way of pipe 55 to the inlet 38 of cylinder 36. Moisture from the air condenses on the evaporators 30 and 31 and falls to the bottom of cabinet 24 and is conducted 25 from the cabinet through a drain pipe 70.

The quantity of refrigerant circulated through the refrigerating apparatus and the relative quantities or rate of flow of refrigerant through the evaporators 30 and 31 are governed by the 30 condition of the air in the room 20. The motor 42 which drives the compressor 35 is cyclically operated and the duration of the phases of operation of the refrigerating apparatus is controlled by the temperature and the relative humidity of the air in the room 20. It is well understood that comfortable temperature varies with the relative humidity of the air. For example, a temperature of 83° F. of the air at 50% relative humidity is considered a comfortable 35 condition of the air. In accordance with the present invention, I desire to maintain the air between 82° F. and 84° F. when the relative humidity of the air is approximately 50% or less and for this purpose I provide a thermostat 72 40 which is connected by a tube 73 to a pressure operated snap switch 74. This switch 74 is arranged to close its contacts when the temperature of the air attains 84° F. and opens its contacts when the temperature is decreased to 82° F. 45 The thermostat bulb 72 and tube 73 contain a volatile fluid which expands and contracts due to increase and decrease in temperature. When the contacts of the switch 74 are closed a circuit is completed to the motor 42. Switch 74 first 50 closes a relay circuit as follows: main 76, wires 77 and 78, switch 74, wire 79, normally closed switch 80, electro-magnet coil 81 and main 82. Coil 81 attracts its armature 83 to cause the same to 55 engage the contact 84 to complete the following motor circuit: main 76, armature 83, contact 84, wire 85, motor 42 and main 82. The motor being 60 operated, it will cause the compressor 35 to reduce the temperatures of evaporators 30 and 31 and when the temperature of the air at the thermostat 72 decreases to 82° F., the snap switch 74 will be opened to break the circuit through the coil 81 whereby the armature 83 will separate from contact 84 and interrupt the motor circuit. 65

70 When the relative humidity of the air in the room is below a predetermined maximum value, the suction lines 57 and 55 are interconnected through the pipes 65 and 67, the valve 66 at this time being open. Under this condition the pressures of the refrigerants in the evaporators 30

and 31 are substantially the same because either evaporator is connected with both cylinders 36 and 37 of the compressor 35 and consequently the temperatures of both evaporators are substantially the same.

The humidity of the air in the room changes due to changes in the environment and due to the direct adding of moisture to the air and, if the relative humidity of the air is high, a mean temperature of the air at 83° F. would be uncomfortable. In order to rectify this condition, I provide for cooling a part of the air to a low temperature and for this purpose I utilize an instrument preferably a humidostat 87, which is connected in parallel circuit relation with the snap switch 74 through wires 88 and 89. This circuit includes a contact 91 and a movable contact 92 which latter is actuated by an arm 93 of the humidostat 87. When the relative humidity of the air is too high, the humidostat 87 actuates 20 its arm 93 to close contact 92 with contact 91 and thereby completes a circuit to the coil 81 paralleling the circuit including snap switch 74 as follows: main 76, wires 77 and 88, contacts 92 and 91, wires 89 and 79, switch 80, coil 81 and main 25 82. It will be apparent therefore that although the temperature of the air is below 82° F. and the snap switch 74 is open, a circuit is completed nevertheless through coil 81 to maintain the motor 42 operating when the relative humidity of 30 the air in the room is too high. This condition will cause a prolonged operation of the compressor 42.

In case of a relative high humidity when the air approximates the desired temperature, it is 35 desirable to remove the excess quantity of moisture from the air without materially lowering the temperature of the air. In order to accomplish this, I provide for varying the differential between evaporators 30 and 31 by increasing the 40 pressure of the refrigerant and likewise the temperature of evaporator 30 and decreasing the pressure of the refrigerant and likewise decreasing the temperature of the evaporator 31. In this manner, a portion of the heat absorbing 45 means is reduced considerably below the dew point of the air so as to cause a greater precipitation of moisture from the air at this portion. In order to vary the pressures in evaporators 30 and 31, I provide for directly connecting evaporator 31 with the cylinder 36 and for directly connecting evaporator 30 with the cylinder 37 by closing the valve 66. The size of the cylinders 36 and 37 are computed relative to the sizes of the evaporators 31 and 30 so that, when these 50 evaporators are directly connected to their respective cylinders, the temperature of evaporator 31 will be lowered below the temperature of evaporator 30. The operation of the valve 66 is governed by the humidostat 87. When the relative humidity of the air in the room is above a predetermined desired maximum, the circuit to the electro magnet 69 is interrupted so that the valve 66 is closed. During normal operation, that is when the relative humidity of the air is 55 below a predetermined maximum, the humidostat 87 is in a position to close a circuit to the coil 69 so as to cause the core 68 to establish intercommunication between suction pipes 55 and 57. The circuit to the electro magnet 69 is traced as follows: main 77, wires 88 and 95, contact 96, movable contact 97, wire 98, electro-magnet 69, wire 99 and main 82. Movable contact 97 is actuated by an arm 101 of the humidostat 87. Thus it is 60 apparent from the foregoing that when the hu- 65 70 75

midity of the air is not above a predetermined maximum, the evaporators 30 and 31 operate at substantially the same temperature because the valve 66 is open and, in case of a relative high humidity, the humidostat 87 operates to prolong the operation of the compressor 35 and establish individual and independent connections between the respective evaporators and cylinders of the compressor whereby to cause an increased precipitation of moisture from the air.

Under some conditions, the relative humidity of the air to be conditioned may be such that the compressor would operate long enough to reduce the temperature of the air to such low degree as to provide an uncomfortably low temperature and, in order to prevent such a condition, I provide for stopping the compressor when the temperature of the air attains a predetermined low value below which temperature the air would be uncomfortable. For this purpose I provide a thermostat 103 which is connected with the snap switch 80 by a tube 104. Bulb 103 and tube 104 contain a volatile fluid which expands and contracts in response to increase and decrease in temperature. When the temperature of the air in the room is decreased, for example, to 76° F., the pressure in the bulb 103 and tube 104 is decreased sufficiently to actuate the snap switch 80 to cause its contacts to be separated. Therefore, regardless whether there is a demand for further dehumidification through the humidostat 87, the circuit of coil 81 through the humidostat 87 will be broken by switch 80 and armature 83 will separate from contact 84 to interrupt the motor circuit.

The fan 27 and motor 28 operate continuously, the motor being connected to the mains as follows: main 76, wires 77 and 106, motor 28, wires 107 and 99 and main 82.

From the foregoing it will be seen that I have provided a refrigerating apparatus which when employed in an air conditioning system, maintains a comfortable temperature under proper humidity conditions and in case the relative humidity is too high, the excess moisture is removed from the air without materially lowering the temperature of the air and in case of an extremely high humidity condition, the temperature of the air is lowered but not too cold for comfort or inefficient operation.

While the form of embodiment of the present invention as herein disclosed constitutes a preferred form, it is to be understood that other forms might be adopted, all coming within the scope of the claims which follow:

I claim:

1. An air conditioning system comprising in combination, a refrigerating apparatus including an evaporator about which air to be conditioned is circulated, an expansion valve responsive to the condition of the refrigerant in the evaporator for controlling the flow of refrigerant to the evaporator, a second evaporator about which air to be conditioned is circulated, said second evaporator being connected in a parallel circuit relation with the first mentioned evaporator, means for withdrawing gaseous refrigerant from the evaporators compressing and condensing the said refrigerant and delivering the same to said evaporators, separate conduits connecting the outlets of the evaporators to said means, a conduit for refrigerant interconnecting said first mentioned conduits, and means responsive to the relative humidity of the air to be conditioned for con-

trolling the flow of refrigerant through the interconnecting conduit.

2. An air conditioning system comprising in combination, a refrigerating apparatus including a plurality of evaporators about which air to be conditioned is circulated, each of said evaporators having an expansion valve of the type which is responsive to the condition of the refrigerant in the evaporator for controlling the flow of refrigerant to the respective evaporator, means for withdrawing gaseous refrigerant from the evaporators compressing and condensing the said refrigerant and delivering the same to said expansion valves, separate conduits connecting the outlets of the evaporators to said means, a conduit for refrigerant interconnecting said first mentioned conduits, and means responsive to the relative humidity of the air to be conditioned for controlling the flow of refrigerant through the interconnecting conduit.

3. An air conditioning system comprising in combination, a refrigerating apparatus including a plurality of evaporators about which air to be conditioned is circulated, each of said evaporators having an expansion valve of the type which is responsive to the condition of the refrigerant in the evaporator for controlling the flow of refrigerant to the respective evaporator, means for withdrawing gaseous refrigerant from the evaporators compressing and condensing the said refrigerant and delivering the same to said expansion valves, said means having a plurality of suction inlets, a conduit connecting the outlet of one of said evaporators with one of said inlets, a conduit connecting the outlet of another of said evaporators to another of said inlets, a conduit for refrigerant interconnecting said first mentioned conduits, and means responsive to the relative humidity of the air to be conditioned for controlling the flow of refrigerant through the interconnecting conduit.

4. An air conditioning system comprising in combination, a refrigerating apparatus including a plurality of evaporators about which air to be conditioned is circulated, each of said evaporators having an expansion valve of the type which is responsive to the condition of the refrigerant in the evaporator for controlling the flow of refrigerant to the respective evaporator, means for withdrawing gaseous refrigerant from the evaporators compressing and condensing the said refrigerant and delivering the same to said expansion valves, said means having a plurality of suction inlets, a conduit connecting the outlet of one of said evaporators with one of said inlets, a conduit connecting the outlet of another of said evaporators to another of said inlets, and means for controlling the rate of flow of refrigerant from one of said evaporators to one of said inlets, said last mentioned means being responsive to the relative humidity of the air to be conditioned.

5. An air conditioning system comprising in combination a refrigerating apparatus including an evaporator about which air to be conditioned is circulated, an expansion valve responsive to the condition of the refrigerant in the evaporator for controlling the flow of refrigerant to the evaporator, a second evaporator about which air to be conditioned is circulated, said second evaporator being connected in a parallel circuit relation with the first mentioned evaporator, means for withdrawing gaseous refrigerant from the evaporators compressing and condensing the said refrigerant and delivering the same to said evap-

orators, said means having a plurality of suction inlets, a conduit connecting the outlet of one of said evaporators with one of said inlets, a conduit connecting the outlet of another of said evaporators to another of said inlets, and means for controlling the rate of flow of refrigerant from one of said evaporators to one of said inlets, said last mentioned means being responsive to the relative humidity of the air to be conditioned.

10. 6. In an air conditioning system, a refrigerating apparatus comprising in combination, an evaporator, an expansion valve responsive to the condition of the refrigerant in the evaporator for controlling the flow of refrigerant to the evaporator, a second evaporator connected in parallel circuit relation with the first mentioned evaporator, means for withdrawing gaseous refrigerant from said evaporators compressing and condensing the said refrigerant and delivering the same to said evaporators, separate conduits connecting the outlets of the evaporators to said means, a conduit for refrigerant interconnecting said first mentioned conduits, and means responsive to a condition of the medium cooled by the evaporators for controlling the flow of refrigerant through the interconnecting conduit.

7. In an air conditioning system, a refrigerating apparatus comprising in combination, a plurality of evaporators each having an expansion valve of the type which is responsive to the condition of the refrigerant in the evaporator for controlling the flow of refrigerant to the respective evaporator, means for withdrawing gaseous refrigerant from said evaporators compressing and condensing the said refrigerant and delivering the same to said expansion valves, separate conduits connecting the outlets of the evaporators to said means, a conduit for refrigerant interconnecting said first mentioned conduits, and means responsive to a condition of the medium cooled by the evaporators for controlling the flow of refrigerant through the interconnecting conduit.

8. In an air conditioning system, a refrigerating apparatus comprising in combination, an evaporator, an expansion valve responsive to the condition of the refrigerant in the evaporator for controlling the flow of refrigerant to the evaporator, a second evaporator connected in parallel circuit relation with the first mentioned evaporator, means for withdrawing gaseous refrigerant from said evaporators compressing and condensing the said refrigerant and delivering the same to said evaporators, said means having a plurality of suction inlets, a conduit connecting the outlet of one of said evaporators with one of said inlets, a conduit connecting the outlet of another of said evaporators to another of said inlets, and means responsive to a condition of the medium cooled by the evaporators for controlling the flow of gaseous refrigerant to one of said inlets.

9. In an air conditioning system, a refrigerating apparatus comprising in combination, an evaporator, an expansion valve responsive to the condition of the refrigerant in the evaporator for controlling the flow of refrigerant to the evaporator, a second evaporator connected in parallel circuit relation with the first mentioned evaporator, means for withdrawing gaseous refrigerant from said evaporators compressing and condensing the said refrigerant and delivering the same to said evaporators, said means having a plu-

rality of suction inlets, a conduit connecting the outlet of one of said evaporators with one of said inlets, a conduit connecting the outlet of another of said evaporators to another of said inlets, a conduit for refrigerant interconnecting said first mentioned conduits, and means responsive to a condition of the medium cooled by the evaporators for controlling the flow of refrigerant through the interconnecting conduit.

10. An air conditioning system comprising in combination, a refrigerating apparatus including an evaporator about which air to be conditioned is circulated, an expansion valve responsive to the condition of the refrigerant in the evaporator for controlling the flow of refrigerant to the evaporator, a second evaporator about which air to be conditioned is circulated, said second evaporator being connected in a parallel circuit relation with the first mentioned evaporator, means for withdrawing gaseous refrigerant from the evaporators compressing and condensing the said refrigerant and delivering the same to said evaporators, separate conduits connecting the outlets of the evaporators to said means, a conduit for refrigerant interconnecting said first mentioned conduits, and means responsive to a condition of the air to be conditioned for controlling the flow of refrigerant through the interconnecting conduit.

11. An air conditioning system comprising in combination, a refrigerating apparatus including an evaporator about which air to be conditioned is circulated, an expansion valve responsive to the condition of the refrigerant in the evaporator for controlling the flow of refrigerant to the evaporator, a second evaporator about which air to be conditioned is circulated, said second evaporator being connected in a parallel circuit relation with the first mentioned evaporator, heat dissipating means including means for circulating refrigerant through the first evaporator for maintaining the same at a certain temperature and means for circulating refrigerant through the second evaporator for maintaining the second evaporator at a different temperature, a conduit connecting the outlet of the first evaporator with the first mentioned circulating means and a conduit connecting the outlet of the second evaporator with the second mentioned circulating means, a conduit for refrigerant interconnecting said first mentioned conduits, and means responsive to a condition of the air to be conditioned for controlling the flow of refrigerant through the interconnecting conduit.

12. The method of controlling the humidity and temperature conditions of air by a mechanical refrigerator employing refrigerant compressing and condensing means and evaporating means including a plurality of evaporators connected at all times in parallel circuit relation, which method comprises, causing air to circulate over the evaporating means; causing the starting of operation of the compressing and condensing means in response to a high temperature condition or a high humidity condition of the air; and while the compressing means is in operation, varying the refrigerating effect of the evaporating means by controlling the flow of refrigerant through one of the evaporators in accordance with changes in one of the said conditions of the air.
